(57) **CLAIM**

The ornamental design for a machining center, as shown and described.

DESCRIPTION

FIG. 1 is a front elevation of a machining center showing the design;

FIG. 2 is a top plan view of the machining center of FIG. 1; FIG. 3 is a left side elevation of the machining center of FIG. 1;

FIG. 4 is a right side elevation of the machining center of FIG. 1;

FIG. 5 is a rear elevation of the machining center of FIG. 1; FIG. 6 is a bottom plan view of the machining center of FIG. 1;

FIG. 7 is a perspective view taken from the front, top and right side of the machining center of FIG. 1;

FIG. 8 is a perspective view taken from the rear, top and right side of the machining center of FIG. 1; and,

FIG. 9 is a perspective view taken from the rear, top and right side of the machining center of FIG. 1, with a rear cover in an open position, a control panel being held on the rear cover.

The broken line showing of the machining center in FIGS. 2, 6, 7, 8 and 9 are included for the purpose of illustrating portions of the machining center and form no part of the claimed design.
